(57) **CLAIM**

The ornamental design for a pet bowl with brook trout surface pattern, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of the pet bowl with brook trout surface pattern of the present design.

FIG. 2 is a rear perspective view thereof.

FIG. 3 is a bottom plan view thereof.

FIG. 4 is a top plan view thereof.

FIG. 5 is a front elevation view thereof.

FIG. 6 is a left side elevation view thereof.

FIG. 7 is a rear elevation view thereof; and,

FIG. 8 is a right side elevation view thereof.
